(57) **CLAIM**

The ornamental design for a camera, as shown and described.

DESCRIPTION

FIG. 1 is a perspective view of a camera showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is an environmental perspective view of the camera supported by a bracket.

The shade lines in the Figures show contour and not surface ornamentation.

The broken line showing of the support bracket in FIG. 8 illustrates the environment of the claimed design and forms no part thereof.

The remaining broken lines in the drawings illustrate portions of the camera and form no part of the claimed design.
